ELECTRODE HOLDER

Frank J. Nowicke, Hanover, Md.

Application July 14, 1942, Serial No. 450,879

1 Claim. (Cl. 219—8)

This invention relates to electrode holders for use in arc welding or the like and more particularly to a novel handle construction for the same and constitutes an improvement of the handle construction shown in my pending application for Electrode holder, Serial No. 427,489, filed January 20, 1942.

The primary objects of the present invention are to provide an electrode holder of simplified construction, using relatively few parts thereby reducing the cost of its manufacture, and reducing the amount of metal used in its construction resulting in a saving of material and increasing the lightness in weight of the holder.

These and other detailed objects of the invention will be apparent from the following description taken in connection with the following drawings, in which—

Figure 1 is a side elevational view taken partly in section of an electrode holder embodying my improvements;

Figure 2 is a top plan view of the holder shown in Figure 1;

Figure 3 is a sectional view taken on the line 3—3 of Figure 2.

Referring to the drawing in detail, the holder comprises a pair of jaw members 10, 11 and a removable handle guard 12. Located within the guard 12 is a connector 13 provided at its rear end with a cavity to receive the wires 14 of an electrical conduit 15. The wires are soldered or otherwise secured to connector 13 to make positive electrical contact therewith. The forward end of connector 13 comprises a flat slotted bar portion 16 to which the rear ends of jaws 10 and 11 are secured in a manner to be described.

The jaw members 10 and 11 are identical and a description of one will suffice for both. Jaw member 10 comprises a flat elongated bar having a bowed portion 17 formed substantially midway thereof. The provision of the bowed portion 17 increases the resiliency of the jaw member and also increases the amount of metal between the forward end of the jaw and the handle portion thereby tending to reduce the transfer of heat from the electrode to the handle.

The forward end of the jaw 10 is provided with a gripping member 18 detachably locked in place by means of a screw 19. Jaw member 10 is further provided with a series of slots 20, 21 and 22. Slots 20 and 22 have no mechanical function in the combination and are provided to minimize the amount of metal used and to reduce the weight of the holder. Slot 21 is provided to receive a stirrup member 23 having a portion 24 inserted between the jaws which are suitably recessed at 25 to receive said portion. The stirrup member

23 is further provided with a removable insulated handle 26 designed to extend rearwardly over the handle of the tool where it may conveniently be manipulated by the operator. It will be apparent that downward movement of the handle from the position shown in Figure 1 will cause separation of the jaws and the electrode, not shown, may then be inserted.

A guard 27 of insulating material may be slipped over the rear ends of the jaws to lodge against the handle member of the tool, the guard being provided with a cutout or recessed portion 28 within which the member 26 may be moved. The guard member 27 protects the hand of the operator from the heat emanating from the electrode and may be varied in size depending on the amount of protection required.

The jaw members 10 and 11 are secured to the connector 13 by means of a pair of threaded bolts 29 and 30. As seen in Figure 1, bar portion 16 of connector 13 is complementary to the rear portions of jaw members 10 and 11 and is clamped therebetween by means of threaded bolts 29 and 30. It is to be noted that bolt 30 is applied before handle member 12 is finally secured whereas bolt 29 is not threaded into place until the handle member is in its final position. The countersunk head 31 of bolt 29 passes through opening 32 in handle member 12 and the free end of the bolt passes through opening 33 of said handle member. As a result of this arrangement, the clamping bolt 29 serves the double function of clamping the jaw structure to the connector member and of locking the handle member in position.

Thus it will be seen that I have described a construction well adapted to produce the various objects and advantages pointed out above. While I have shown a preferred embodiment of the invention, it will be understood that the invention is not to be limited to the form shown but may be modified within the scope of the appended claim.

What I claim is:

An electrode holder comprising a pair of jaw members, a guard member, a connector within the guard member, said connector comprising a tubular member having a flat portion extending therefrom, said tubular portion housing one end of an electrical conduit, said jaw members having rearwardly extending flat portions, and a pair of bolts securing the flat portions of the jaw members to the flat portion of the connector, one of said bolts passing through the guard member to lock said guard member to the connector.

FRANK J. NOWICKE.
